ATTORNEY.

UNITED STATES PATENT OFFICE.

EDWIN F. GUTH, OF ST. LOUIS, MISSOURI, ASSIGNOR TO LUMINOUS UNIT COMPANY, OF ST. LOUIS, MISSOURI, A CORPORATION OF MISSOURI.

STREET-LAMP.

1,325,940.

Specification of Letters Patent. Patented Dec. 23, 1919.

Application filed November 27, 1916. Serial No. 133,557.

To all whom it may concern:

Be it known that I, EDWIN F. GUTH, a citizen of the United States, residing at St. Louis and State of Missouri, have invented 5 a certain new and useful Improvement in Street-Lamps, of which the following is a specification.

Street lamps, with which I am familiar, are designed to reflect the light downwardly 10 upon the side walk and street, with the result that there is a pall of intense blackness just above the light, intensifying the darkness, thus in a measure defeating the purpose of the illumination.

15 My invention has for its object to provide a street light, which will not only reflect the light downwardly upon the side walk and street, but which will also have means provided to reflect the light upwardly 20 and to flood-light the buildings on the street.

25 My means of accomplishing the foregoing objects may be more readily understood by having reference to the accompanying drawings, which are hereunto annexed and are a part of this specification, in which:

Figure 1 illustrates a sectional view of a lighting fixture including the invention; and

Fig. 2 illustrates a plan view of a fragment of a strap.

Similar reference numerals refer to similar parts throughout the entire description.

As shown in the drawings, 1 is the base which is attached to any suitable standard.

35 Mounted upon the base, and extending upwardly therefrom are arms 2 and 3, spaced at equidistant points about the periphery of the base 1, forming a cage which supports the lower globe 4, which is preferably 40 formed of translucent glass. The top 5 of the base 1, is provided with upwardly extending standards 6 and 7. Upon these standards is mounted a strap 8, to which is secured the lamp socket 9, from which depends the electric light bulb 10. An annular member 11, is secured to the upper ends of the standards 6 and 7 by means of nuts 12, which hold the said ring 11, tightly against the strap 8. The surface of this ring 11, is 45 preferably finished in enamel, or some other finish which will assist the said ring in reflecting the rays of light from the bulb, thus 50 increasing the efficiency of the light for a

side-walk and street lighting, at the same time operating to shield from view the mechanism in the upper half of the lamp.

A band 13, preferably formed of metal is mounted upon the top of the arms, which is shouldered as at 14, and provided with a plurality of openings for the insertion of 60 set screws 15, which secure a ring 16 to the band 13, this latter ring operating to clamp and hold a hemispherical glass globe 17, which forms the upper part of the street light. This globe is preferably formed of 65 translucent glass. Cast or formed upon the strap 8 is a member 18, to which is pivotally secured a reflector 19. The reflector 19, has secured to its rear wall a U-shaped strap, which is formed in two parts, 20 and 21, the 70 two parts being secured together by means of bolts 23, which are held in position by means of wing nuts 22, the bolts being mounted in slots formed adjacent the ends of the part 20, of the U-shaped strap, thus 75 providing simple and easy means for adjusting the focus of the electric light bulb 24, with relation to the reflector 19.

80 A suitable socket 25, for the electric light bulb 24, is secured to the strap 21. An electric cable 26, leading to a source of supply (not shown) carries the current to the socket 25. The annular member 11, is provided with an opening 27, adjacent the lower edge 85 of the reflector 19, thus permitting the reflector to be moved up and down for the purpose of directing the flood-lighting upon the building in the desired place. By reason of the presence of the opening 27, the upper reflector may enter the said opening and 90 increase the range of movement of said reflector beyond that which it would have if the opening were not present.

95 It will be apparent from the foregoing description that this construction will furnish a highly efficient illumination of the street and side walk, while a portion of the light from the bulb 24, will tend to dissipate in a measure the intense blackness immediately above the street lamp while the reflector will direct a portion of the rays from the light bulb 24, upon the building, to produce a flood-lighting effect, the whole resulting in the production of a brilliant street illumination.

100 Having described my invention what I re-

gard as new and desire to secure by Letters Patent is:

1. The combination of a globe, with an inverted hemispherical globe thereabove, an electric light bulb mounted within the first mentioned globe, a reflector pivotally mounted above said light, a light bulb adjustably mounted within said reflector, means to separate the portion containing the reflector from the remaining portion.
2. The combination of a globe formed of translucent glass, with a hemispherical globe of clear glass located thereabove, an electric light bulb mounted within the translucent glass, a parabolic reflector pivotally mounted above said light bulb, a light bulb mounted within said reflector, opaque means to separate the portion containing the reflector from the remaining portion.
3. The combination of a globe of translucent glass, with an inverted hemispherical globe of clear glass detachably secured adjacent the top of the translucent globe, an electric light bulb suspended within the translucent glass, a parabolic reflector pivotally mounted above said light bulb, a light bulb adjustably mounted within said reflector, opaque means to separate the portion containing the reflector from the remaining portion.
4. The combination of a globe of translucent glass, with an inverted hemispherical globe of clear glass, means to detachably secure said globes one above the other, an electric light bulb suspended within the translucent glass, a parabolic reflector pivotally mounted above said light bulb, an electric light bulb adjustably mounted within said

reflector, means to separate the portion containing the reflector from the remaining portion.

5. A street light comprising the combination with a glass globe, formed of an upper and lower portion, detachably secured together, means to divide the two portions into chambers, said means possessing reflective qualities, on its surface, means to illuminate both of said chambers, and adjustable means to direct said illumination in one chamber in a predetermined direction.

50 6. A street light comprising the combination with a glass globe formed with an upper and lower portion, means to detachably secure said portions, means to divide the two portions into chambers, said means possessing reflective qualities on its surface, means to illuminate both of said chambers, adjustable means to direct some of said illumination in a predetermined direction and adjustable means to focus a portion of the electric light rays.

65 7. A street light comprising the combination with a glass globe formed with an upper and lower portion, means to detachably secure said portions together, means to divide the two portions into chambers, said means possessing reflective qualities on its surface, means to illuminate both of said chambers, adjustable means to direct some of said illumination in a predetermined direction and adjustable means to focus a portion of the electric light rays, and means to secure said adjustment when made.

70 In testimony whereof, I have signed the foregoing specification.

EDWIN F. GUTH.
